United States Patent Office.

JOHN W. SANFORD, OF BATH, NEW YORK.

Letters Patent No. 67,915, dated August 20, 1867.

IMPROVEMENT IN COMBINED GATE AND FENCE.

The Schedule referred to in these Letters Patent and making part of the same.

TO ALL WHOM IT MAY CONCERN:

Be it known that I, JOHN W. SANFORD, of Bath, Steuben county, and State of New York, have invented a new and improved Double Three-Rail Balanced Gate with a Two and Three-Rail Picket-Fence attached to gate, in combination with a sill to be set under ground; and I do hereby declare that the following is a full and exact description thereof, reference being had to the accompanying drawings, and to the letters of reference marked thereon.

To enable others skilled in the art to make and use my invention, I will proceed to describe its construction and operation.

The gates are made with ordinary rails and pickets put on with screw-bolts of proper size. The pickets of the fence are also put on in the same manner.

The gate *a* is hung with a screw-bolt, *b*, through the top of the gate-post *c* and of the upper rail of the gate *d*, and when raised for passing through, balances on said bolt by means of a sufficient weight of lead, iron, stone, or sand, *e*, placed on the projection end of the top rail of the gate to hold them while open to their place. The posts of the gates and fence are framed with a tenon set in a mortise of a sill, *f*, of a sufficient size. At the centre point of the gates is a centre-block, *g*, framed in the sill, with gains in both sides for the ends of the lower rails to set in when shut, with a spring-catch to hold the gate down and shut. At the end of the top of rails, to the gate where they come together when shut, on one side is a mortise, and a tenon on the other top rail of the other side of the gate, so made as to fit in each other, with a pin through the mortise and joint for a lock and guard. The posts of the gates are mortised from the top down to a sufficient distance of the sill of the gates, to allow the rails to work through. The lower rails of the gates, with the pickets when hoisted, drop down, by their weight, to the posts. The tenons of the posts of the gates and fence are set in the mortise of the sills with a coating of tar, to preserve them from decay. The projecting end of the top rails of the gates is guarded with a guard-hook made of iron, and fastened to the top rail of the fence, at the end of the top rail of the gates which sets over it, so as to make the gates at the centre joints as stiff and strong as a single gate would be. These gates and fence front on both sides. The pickets on gates, and fence, and posts, to be put on in shape and size corresponding to size.

What I claim as my invention, and desire to secure by Letters Patent, is—

The manner of putting together these double gates and posts with fence, in combination with sills to be set in the ground.

JOHN W. SANFORD.
